CABLE AND ROPE WINDING APPLIANCES
SUCH AS WINCHES AND HOISTSWilfred Charles Treloggen, Brockenhurst,
EnglandApplication August 10, 1934, Serial No. 739,359
In Great Britain August 16, 1933

6 Claims. (Cl. 242—158)

This invention relates to cable and rope winding appliances, such as winches and hoists and has for its object the provision of means to facilitate coiling or laying of the cable around the winding drum so as to prevent "over-riding" and "snagging" and prevent damage to and eliminate the wear due to feeding the cable on to a drum which has only one movement, i. e. that of rotation, it being well known that bad winding results in ordinary winches, hoists and similar winding appliances in which the drum has such a single movement.

The present invention accordingly provides for a transverse or axial reciprocatory movement of the drum relative to a fixed feeding point during the rotation of the drum so that each convolution of the cable is guided positively into the correct position. This relative transverse or axial movement is equal to the thickness of the cable for each convolution thereof, or, in other words, for each revolution of the drum, so that better winding results. At each end of the drum movement when the cable reverses and coils back over that previously laid, a complete revolution of the drum is allowed before the return movement commences so as to ensure that the cable fills up the entire length of the drum before winding back over itself.

Broadly, the invention consists in mounting the winding drum loosely upon an axle so as to be capable simultaneously of rotation and of a transverse axial reciprocatory movement in relation to a fixed feeding eye or the equivalent, the total transverse movement of the drum being approximately equal to the length of the winding barrel, whilst the rate of transverse movement is adjusted so as to amount to a distance equal to the thickness of the cable for each revolution of the drum.

The invention is illustrated in the accompanying drawings wherein:—

Figures 1, 2 and 3 are respectively a front elevation, an end view and a longitudinal cross-section showing diagrammatically the essential working elements of appliance and

Figures 4 and 5 are front and end elevations of a winch in accordance with the invention suitable for attachment to a motor tractor.

In an embodiment of the invention, a flanged drum 1 is slidably mounted upon a horizontal axle 2 which extends between a pair of end frames 3, the length of the axle 2 being such as to permit a sliding movement thereof of the drum 1 of a distance not less than the distance between the drum flanges. The peripheries of

the flanges 4 of the drum 1 are provided with teeth which mesh with a long gear pinion 5 extending between the side frames 3 and arranged parallel to the drum axle 2. This pinion 5 derives a rotary motion through intermediary gearing 6 from a suitable power shaft 7 and thus effects rotation of the drum 1 throughout its transverse reciprocatory movement. This latter movement of the drum 1 is effected by a slider crank motion. This motion consists of a crank disc 8 rotatably mounted on a fixed axle 9 located approximately midway between the side frames 3 of the appliance, the said crank disc 8 having a projecting pin 10 which slidably engages within the slot 11 of a slide 12 which is supported upon guide rods 13 arranged parallel to the drum axle 2. The slide member 12 has sidewardly projecting arms 14 which are adapted to contact with the flanges 4 of the drum 1 so that when the crank disc 8 rotates, its pin 10 moves the slide 12 from side to side and the slide 12 in its turn effects a reciprocatory movement of the drum 1. The crank disc 8 has peripheral teeth 15 which engage with a worm gear 16 driven at suitable speed through gearing 17 from the pinion 5. The shaft of the pinion 5 is provided with a brake drum 18.

The arms 14 of the drum reciprocating means are of less length between their extremities than the distance between the flanges 4—4 of the drum, therefore, the initial reverse movement of the drum reciprocating means is idle with respect to the drum to provide the result heretofore pointed out, namely at each end of the drum movement, when the cable reverses and coils back over that previously laid, a complete revolution of the drum is permitted before the return movement of the drum commences so as to insure the cable filling up the entire length of the drum before winding back over itself, thereby providing evenly stacked layers of cable on the drum.

The cable is delivered to the drum 1 through a fixed feeding eye 19 or the equivalent, such as between a pair of freely mounted rollers, said feeding eye or the like being disposed above the crank disc 8.

Figures 4 and 5 of the drawings illustrate the embodiment of the foregoing invention in one of its commercial forms, namely a construction suited as an attachment for a motor tractor. Clearly, other forms of embodiment may be resorted to, but the figures above noted serve to illustrate the range of embodiment.

I claim:

1. A winch of the class described including side frames, a shaft mounted between said side frames,

- 5 a gear pinion journaled in the side frames and having gear teeth extending from end to end thereof, a winding drum mounted to rotate and slide on the shaft, gear teeth associated with the drum for continuously meshing with the teeth of the gear pinion during the rotary and sliding movement of the drum, means for reciprocating the drum, and cable guiding means fixed with reference to the drum.
- 10 2. A winch of the class described including side frames, a shaft mounted between said side frames, a gear pinion journaled in the side frames and having gear teeth extending from end to end thereof, a winding drum mounted to rotate and slide on the shaft, gear teeth associated with the drum for continuously meshing with the teeth of the gear pinion during the rotary and sliding movements of the drum, said means comprising a slide having means for engaging the drum to shift it back and forth between the side frames, a power driven crank disk having a sliding pin engaging with the slide, and cable guiding means fixed with reference to the drum.
- 15 3. A winch of the class described including side frames, a shaft mounted between said side frames, a gear pinion journaled in the side frames and having gear teeth extending from end to end thereof, a winding drum mounted to rotate and slide on the shaft, gear teeth associated with the drum for continuously meshing with the teeth of the gear pinion during the rotary and sliding movements of the drum, said means comprising spaced guide rods spanning the side frames, drum reciprocating means mounted on the rods, a power driven crank disk operatively connected with said drum reciprocating means to effect its movement, and cable guiding means fixed with reference to the drum.
- 20 4. A winch of the class described, including side frames, a fixed shaft mounted between said side frames, a power driven gear pinion journaled in the side frames and having gear teeth extending from end to end thereof, a winding drum mounted to rotate and slide on the shaft, gear teeth associated with the drum for continuously meshing with the teeth of the gear pinion during the rotary and sliding movements of the drum, means for
- 25 reciprocating the drum including spaced guide rods, a shiftable member mounted on said rods and having means for engaging alternately with opposite flanges of the drum, a guideway in said shiftable member, a fixed axle shaft, a crank disk mounted on said fixed axle shaft, power means for rotating said crank disk, a member carried by the crank disk and slidable in said guideway whereby rotation of the disk will reciprocate the drum shifting means, and cable guiding means fixed with reference to the drum.
- 30 5. A winch of the class described, including side frames, a shaft mounted between said side frames, a gear pinion journaled in the side frames and having gear teeth extending from end to end thereof, a winding drum mounted to rotate and slide on the shaft, gear teeth associated with the drum for continuously meshing with the teeth of the gear pinion during the rotary and sliding movement of the drum, cable guiding means fixed with reference to the drum, and means for reciprocating the drum, said means comprising guide means supported by the side frames, drum reciprocating means mounted on said guide means and including lateral arms of less width than the distance between the drum flanges to permit the said means to have an initial idle movement in both directions of movement with respect to the drum, and a power driven crank disk for moving said drum reciprocating means.
- 35 6. A winch of the class described, including, side frames, a shaft mounted between said side frames, a gear pinion journaled in the side frames and having gear teeth extending from end to end thereof, a winding drum mounted to rotate and slide on the shaft, gear teeth associated with the drum for continuously meshing with the teeth of the gear pinion during the rotary and sliding movement of the drum, cable guiding means fixed with reference to the drum, and means for reciprocating the drum, said means including means whereby each initial reverse movement of said means for reciprocating the drum is idle with respect thereto to permit the initial coil of each superimposed layer of cable to overlie the last coil of the previous layer.

WILFRED CHARLES TRELOGGEN.
